UNITED STATES PATENT OFFICE.

WILLIAM F. STUCKEMAN, OF PITTSBURGH, PENNSYLVANIA.

METHOD OF AND APPARATUS FOR CASTING WIRE TERMINALS.

Application filed March 28, 1927. Serial No. 178,866.

This invention relates to a method of and apparatus for forming terminals on connector cables, or the like.

Among the objects of the invention are to provide a machine for forming terminals on wire cables, of simple and durable mechanical construction, and particularly to form such terminals by die-casting them on cable ends in a simple and inexpensive manner.

10 Another object of the invention is to provide apparatus for forming terminal ends on such cables, in large quantities, of uniform quality throughout, and without the expensive finishing operations now necessary.

15 Terminal ends for stranded cables have heretofore been difficult to produce by the casting process on account of the difficulty of sealing off the portion where the terminal ends, to prevent the leakage or flow of metal 20 out of the spaces between strands. This condition is made more difficult in die-casting operations on account of the fact that the molten metal is conducted to the die under pressure which requires that the portion of 25 the cable adjacent the portion on which the terminal is formed must be tightly sealed to resist the pressure of the fluid metal in the die.

Cables formed of stranded wires are used 30 for connecting the adjacent ends of rails in tracks for street railways, railroads, etc. The ends of the cables are run through holes in the webs of adjacent rails, and a permanent connection made by driving a wedge in the 35 hole beside the cable. A much better electrical connection is secured where the end of the wires is covered by an integral metal terminal, such as that described herein.

In accordance with the present invention I 40 provide a machine comprising a vat or tank provided with a heater in which the metal for the die-casting operation is melted and stored and which has associated therewith a mold or die element adapted to receive the 45 end of a stranded cable on which the terminal is to be formed. Cooperating with the mold or die are a plurality of tamping elements adapted to seal off the edge of the cable by tamping a sealing material such as asbestos, cork, or other suitable packing material, around the edge of the cable member above 50 the portion on which the terminal is to be cast. The machine is further equipped with means for depositing the sealing material 55 in its proper position around the cable.

These several functions are carried out semi-automatically by suitable mechanism at the proper time through the manipulation of a single operating medium whereby the casting of terminal ends is greatly facilitated and 60 performed in a minimum time.

In the accompanying drawings, Fig. 1 is a front elevational view of a die casting apparatus embodying the principles of this invention; Fig. 2 a side elevational view thereof; 65 Fig. 3 a plan view; Fig. 4 an enlarged detail of a portion of the die element illustrating its manner of operation; Fig. 5 a sectional elevation of the die; and Fig. 6 an elevational view of the completed terminal. 70

Referring to the several figures of the drawings, the structure therein illustrated comprises a container or tank 1 mounted on suitable pedestals 2 and having a cover 3, providing an enclosed chamber for molten 75 metal. The metal is heated by a burner 4 provided underneath the container.

Suspended in the container is a cylinder 5 having a piston 6 operatively disposed in one end thereof, its other end terminating in a conduit 7, which extends upwardly to the top of the casing and projects outwardly through a panel 8. The cylinder 5 is further provided with an opening 9 through which the molten metal flows into the cylinder and from which it is displaced under pressure by 80 downward movement of the piston member 6, through the conduit 7. 85

The piston 6 is actuated by a plunger 10, which is pivotally connected at 11 to a lever 12, supported on a rod 13, secured to a fixed lug 14 that projects from one side of the casting member 1. The lever 12 is biased by a coil spring 15 to normally hold it in its raised position, which is the position in which the 90 piston 6 is disposed above the opening 9 of the cylinder, as shown in Fig. 2.

Mounted on the front of the panel member 8 is a movable die block 16, having an opening 17 corresponding in its dimensions to the 100 size of the terminal which it is desired to form on a cable. The opening is provided with a constricted portion 18 of the diameter of the outer portions of the cable member on which the terminal is to be formed.

As shown in Figs. 1 and 4 of the drawings, the die block may be separated along the line 19, which is coaxial with the opening 17, by moving the portion 20 of the die in a slide or guide-way 21. The movable portion of 110

the die is actuated by a lever 22 which is pivotally connected at 23 to an extending frame portion 24 secured to the panel 8. The mold or die is opened and closed for the purpose of 5 removing the terminal after it is formed and to make the opening 17 accessible for cleaning.

Underneath the die 16 is a block 25, having a passage 26 which communicates with the 10 passage 27 of the neck portion 28 of the conduit 7 leading to the pressure cylinder 5. Block 25 is shown provided with an electrical heating element 29 to maintain the metal in the passage 26 in a molten state, and a gas 15 heater 30 is provided underneath the neck portion 28 of the conduit member to prevent freezing of the metal in the passage of the conduit. Other heating means may be used, where and as may be desirable.

20 Referring to Figs. 5 and 6 of the drawings, the die block 16 is shown as having an elongated opening 17 of the shape of the terminal 31 (Fig. 6), that is to be formed on the end of a cable 32. Above the opening 17 is a constricted portion 33 of a diameter corresponding to the outer dimension of the cable 32 and the upper portion of the die 16 is provided with a counter-sunk bell-mouthed recessed portion 34 for receiving a sealing agent 35 25 such as asbestos, cork, or other suitable heat-resistant caulking material adapted to be tightly packed around the cable to seal off the portion 17 on which the terminal is to be formed.

30 The sealing material 35 is packed around the cable 32 by a pair of tamping members 36 having relatively long shank portions 37 which are mounted for oscillatory movement in guides 38 secured to panel member 8. Guides 38 are 35 provided with extensions 39, the end portions 40 of which are bent over to lie in the path of travel of tamping rods 37. Secured to the portion 40 and the ends of rod 37 are coil springs 41 which normally bias the tamping 40 members to their raised position. The ends of the rods 37 are provided with extensions 42 to which links 43 are pivotally connected at 44. The links are pivotally joined at their opposite ends and connected at 45 to a vertically movable actuating member 46 that is disposed in a guide 47 provided in panel member 8. The member 46 is connected at its upper extremity to a bar 48 the lower portion of which is pivotally connected at 49 to a lever 50 that is pivotally mounted to an extending portion 51 of the panel member 8. The lever 50 is connected by a link 52 to a pedal 53 (Fig. 2), which is pivotally connected to one of the legs 2 of the machine 55 base. The arrangement of the tamping members 36 and their mechanical linkage with the pedal 53 is such that when the pedal is depressed the tamping members are pressed downwardly against the resistance of the 60 spring 41 to force the sealing material 35 in

the counter-sunk portion 34 of the die, filling the crevices of the cable strands above the mold cavity, thereby sealing off the opening 18 in the die to prevent leakage.

70 The sealing material 35 which is preferably comminuted asbestos, or cork, is automatically fed to the die block by means of the following mechanism. See Figs. 2 and 3: A hopper 55 in which the sealing material is stored is mounted on the cover member 3 of the tank 1. The hopper at its lower portion is provided with a cylinder 56 having a turned-down end portion or nozzle 57 disposed above the counter-sunk recess 34 of the die block. A piston 58 is operatively disposed for axial movement in the cylinder 56 and is attached at one end to a link 59, one end of which is pivotally connected to a bell crank lever 60. The lever 60 is fulcrumed at 61 to an extension portion 62 of the cover 3 and its other end is connected for sliding engagement with a lever 60^a which is pivoted at 61^a to the cover 3. One end of lever 60^a is connected to a link 63 which is disposed in a guide 65 and biased by a coil spring 64 to normally hold the piston 58 in its extended position. The upper portion of the link 63 is connected by an offset bracket 66 to bar 48 of the tamping mechanism and is adapted to be actuated by movement of the latter.

80 As shown in Fig. 1, panel member 8 is provided with an offset portion 67 for mounting a nozzle 68 leading to a source of compressed air, the nozzle being disposed coaxially with the opening 17 of the die for the purpose of 85 cleaning the latter by means of an air blast. The nozzle 68 is provided with a valve 69 having a handle or lever portion 70 which is manipulated to apply the compressed air to the die.

90 The operation of this machine is briefly as follows: As shown in Fig. 5, the end of the stranded cable 32 on which the terminal is to be formed is inserted in opening 18 of the die. The operator then steps on pedal 53 which 95 actuates piston member 58 for inserting sealing material 35 in recess 34 of the die member, and the tamping mechanism. The mechanism is timed so that piston 58 will press out a portion of packing in advance of the movement of tampers 36, which then engage and firmly pack the material against the cable strands and around the bottom of recess 34, sealing off opening 17 and preventing escape 100 of molten metal.

105 The operator next presses down on lever 12 at the same time keeping his foot on pedal 53. Downward movement of lever 12 lowers piston 6 in its cylinder 5, causing a displacement of molten metal through the passage of 110 conduit 7 into block 25 underneath die 16, and from the conduit passage it passes upwardly through passage 26 into the terminal opening 17 of the die block. The operator 115 then releases both lever 12 and pedal 53 and 120

125 65 130 130 130

- throws lever 22 in the direction to open the die block by moving the portion 20 thereof in its guide 21. The cable is then removed with terminal 31 formed on the end thereof as shown in Fig. 6. The air blast is turned on to blow out any foreign particles which may have dropped in the die from the recess 34, a new cable is inserted, and the operation repeated as described.
- 10 The method of forming terminals on stranded cable and the apparatus therefor described herein provides a simple and efficient means for forming terminals on cables, of uniform quality, and in relatively large quantities, with a minimum of labor, and a minimum waste of material. The machine is particularly designed to eliminate a number of preliminary operations preparatory to the die casting of the terminal ends.
- 15 Although only one embodiment of the invention has been herein illustrated and described, various modifications may be made in the details of construction and in the arrangement of the several cooperating parts 25 without departing from the principles herein set forth.

I claim:

1. A machine for casting metal terminals on cables, comprising a die open at one end to receive the end of a cable and communicating at its other end with a source of molten metal, means for sealing the die at its open end after the cable has been inserted therein, and means for conducting molten metal under pressure into the die.
2. A machine for forming terminals on cables, comprising a die open at one end to receive the end of a cable and communicating at its other end with a source of molten metal, tamping members cooperating with said die and adapted to pack a sealing material around the cable to close the opening in said die after the cable has been inserted therein, and means for conducting molten metal under pressure into the die.
3. A machine for forming terminals on cables, comprising a die open at one end to receive the end of a cable and communicating at its other end with a source of molten metal, tamping members cooperating with said die and adapted to pack a sealing material around the cable to close the opening in said die after the cable has been inserted therein, a pedal-operated actuating mecha-

nism for said tamping members, and means 55 for conducting molten metal under pressure into the die.

4. A machine for forming terminals on cables, comprising a die open at one end to receive the end of a cable and communicating 60 at its other end with a source of molten metal, tamping members cooperating with said die and adapted to pack a sealing material around the cable to close the opening in said die after the cable has been inserted therein, a pedal 65 operated actuating mechanism for said tamping members, means operative by said pedal for feeding sealing material to the mouth of said die, and means for conducting molten metal under pressure into the die. 70

5. A machine for forming terminals on cables, comprising a container for molten metal, a die mounted thereon having an opening for receiving a cable and communicating through a passage with the interior of the 75 container, a heater for said die, a plurality of tamping members cooperatively associated with said die, mechanism for actuating said tamping members to pack a sealing material around the cable in the region of the die opening, and means for conducting molten metal 80 to said die.

6. A machine for forming metal terminals on stranded cable ends, comprising a two-part mold having a restricted portion adapted to loosely engage a cable positioned with its end in the mold cavity, the mold having a flared mouth above such restricted portion, tampers adapted to enter said flared portion and to compress a packing material around 90 the cable in said portion, means to operate said tampers, and automatic means to supply packing material to the mouth of the mold before tamping.

7. The combination set forth in claim 3, 95 plus a reservoir for storing granular tamping material, and means after each casting operation to supply new packing material to be tamped.

8. The method of forming metal terminals 100 on stranded conductor cables, comprising positioning the cable end in a die cavity, tamping a packing material in the mouth of the die cavity about the cable, and forcing molten metal into the die to form a terminal on 105 and about the cable end inside the packing.

In testimony whereof, I sign my name.

WILLIAM F. STUCKEMAN.
